CLAIM

The ornamental design for a martini ice mold, as shown and described.

DESCRIPTION

FIG. 1 is a front view of a martini ice mold showing my new design;

FIG. 2 is a side view of FIG. 1;

FIG. 3 is a top view of FIG. 1;

FIG. 4 is a bottom view of FIG. 1;

FIG. 5 is a top and side view of FIG. 1;

FIG. 6 is a bottom and side view of FIG. 1;

FIG. 7 is a side view of a cap insert for the martini ice mold of FIG. 1;

FIG. 8 is a top view of FIG. 7;

FIG. 9 is a bottom view of FIG. 7;

FIG. 10 is a bottom and side view of FIG. 7; and,

FIG. 11 is a top and side view of a martini ice mold with cap insert in an exemplary tray use.

The broken lines are for illustrative purposes only and form no part of the claimed design. The top and bottom portions of the claimed design are shown separately for clarity of illustration.
